UNITED STATES PATENT OFFICE.

WILLIAM H. BRIGHT, OF HAMPSTEAD, MARYLAND.

WATER-PIPE.

No. 926,092.

Specification of Letters Patent.

Patented June 28, 1900.

Application filed February 27, 1899. Serial No. 630,639.

To all whom it may concern:

Be it known that I, WILLIAM H. BRIGHT, a citizen of the United States, residing at Hampstead, in the county of Carroll and State of Maryland, have invented a new and useful Water-Pipe, of which the following is a specification.

The objects of the invention are, generally, the provision, in a merchantable form, of a device of the above mentioned class which shall be inexpensive to manufacture, facile in operation and devoid of complicated parts; specifically, the provision in a novel and improved form, of a device adapted to be longitudinally mounted in the interior of a water pipe, whereby when the water in the pipe is turned into ice the expansion due to the freezing of the water may be received by such device, instead of being carried into the pipe itself; other and further objects being made manifest hereinafter as the description of the invention progresses.

The invention consists in the novel construction and arrangement of parts herein-after described, delineated in the accompanying drawings, and particularly pointed out in that portion of this instrument wherein patentable novelty is claimed for certain distinctive and peculiar features of the device; it being understood that within the scope of what is hereinafter thus claimed, divers changes in the form, proportions, size and minor details of the structure may be made without departing from the spirit or sacrificing any of the advantages of the invention.

Similar numerals of references are employed to denote corresponding parts throughout the several figures of the drawings.

In the accompanying drawings---Fig. 1 shows my invention in vertical longitudinal section; Fig. 2 is a vertical transverse section thereof. Fig. 3 shows a modified form of my invention in top plan, parts being shown in section.

In the accompanying drawings, the numeral 1 denotes a number of pipe sections which are attached together by means of couplings 2, threaded thereon. These pipe sections may be of any form and the coupling by which they are united may be of any construction, the particular pipe and coupling shown being merely one embodiment of the invention. Each length of pipe

is provided with a core 3, longitudinally disposed in the interior of the pipe, the terminals of the core 3 being attached to the said pipe near its ends. This core 3 may be attached to the pipe by solder, rivets, or any other suitable means, it being understood that the terminals of the core are spaced inward from the terminals of the pipe a distance sufficient to allow for any sort of a coupling being made between the several sections. The core 3 is surrounded by a resilient covering 4, the covering 4 being slightly shorter than the core 3, leaving the ends of the core bare, as denoted by the numeral 5, whereby the core may readily be soldered to the pipe, or attached thereto by any other suitable means.

In its preferred form the core 3 is cylindrical in cross section, and the covering 4 is likewise made cylindrical. The core 3 may be a metallic rod or piece of wire, and the covering 4, in its preferred form, being fashioned from rubber, the said rubber being sterilized, or being chemically pure, in order that the water contained in the pipe may not be contaminated thereby.

In Fig. 3 I have shown a slightly modified form of my invention. In the form there shown, the core is made somewhat longer than the pipe section in which it is mounted so that the ends of the core extend beyond the ends of the pipe section, the extending portion of the core being denoted by the numeral 6. Some distance back from the extremities of the core the resilient covering 4 is cut away as denoted by the numeral 7, leaving a portion of the core bare, which may be attached to the pipe section by means of solder or otherwise after the manner described in connection with Figs. 1 and 2. The advantages incident to the form shown in Fig. 3 are that there is no unprotected place within the coupling 2 where the freezing water could burst the pipe. Not only are the ends of the pipe which lie within the coupling protected, but, since the extremities of the portion 6 in one member extend past the bare portion of the other member, there is no opportunity for an uncontrolled expansion at the point where the resilient covering is cut through to provide a place of expansion. The resilient covering in the form shown in Fig. 3, is made shorter than the core of wire proper, as was done in Figs. 1 and 2, the shortening

however, in the case of Fig. 3 being caused by removing portions thereof intermediate, instead of at the ends of the core.

As the water in the pipe freezes the resilient covering 4 of the core 3 will yield under the expansion of the freezing water. The compression of the covering 4 thus produced will prevent the expansive effort of the ice from being transformed into a bursting stress within the pipe sections 1.

The diameter of the covering 4 will be determined by the diameter of the pipe within which the device is mounted, the coefficient of elasticity of the material from which the covering 4 is fashioned also serving to determine the diameter of the resilient portion of the device. The diameter of the pipe and the coefficient of elasticity of the material from which the covering 4 is fashioned, being known, the size of the said covering 4 may be readily computed; or, if desired, the size of the covering 4 may be determined experimentally.

The core 3 which preferably is of metal, serves to retain the device in place, and the terminals of this core 3, protruding beyond the covering 4, are adapted to receive the means whereby the device is attached to a pipe. The covering 4 is of substantially the same cross section throughout its length, and being retained securely in position longitudinally of the pipe section, by means of the metal core 3, it cannot readily become bent, interfering with the flow of the liquid in the pipe, and serving as a lodging place for any dirt or foreign matter which may be carried in suspension by the liquid in the pipe.

It will be seen, from the foregoing, that my invention presents, in a simple and inexpensive form, a thoroughly effective means whereby water pipes may be prevented from freezing and bursting in the winter season.

Having thus described my invention, what I claim as new, and desire to protect, by Letters Patent, is:—

1. In a device of the class described, a pipe; a core disposed within the pipe, and being attached to the pipe near the end thereof; a resilient covering surrounding the core and being shorter than the core.

2. In a device of the class described, a pipe; a core disposed longitudinally of the pipe in the interior thereof, and being attached to the pipe near the ends thereof; and a resilient covering surrounding the core and being rigidly attached thereto, the covering being shorter than the core.

3. The combination with a pair of pipe sections, of a core disposed in each section and arranged to extend terminally into the other section; and resilient coverings surrounding the cores, the said coverings being cut away to provide places of attachment between the cores and the pipe sections; the terminal extension of each core, with its resilient covering, being arranged to extend past the bared portion of the other core.

In testimony that I claim the foregoing as my own, I have hereto affixed my signature in the presence of two witnesses.

WILLIAM H. BRIGHT.
